his attorney

UNITED STATES PATENT OFFICE.

PASQUALE GIANNONE, OF PHILADELPHIA, PENNSYLVANIA.

BOATSWAIN'S SEAT.

Application filed October 2, 1920. Serial No. 414,194.

To all whom it may concern:

Be it known that I, PASQUALE GIANNONE, a citizen of the United States, and a resident of Philadelphia, in the county of Philadelphia and State of Pennsylvania, have invented a new and useful Boatswain's Seat, of which the following is a specification.

My invention is a suspension seat for boatswains or repairmen and its principal object resides in the provision of a suspension seat or device which will comfortably support a person from the top of a structure to enable him to perform certain labors.

A further object of the invention resides in the provision of a suspension seat of this type which will permit the person to have free movement of his arms while suspended from the top of a mast, pole or other structure.

It is another object of the invention to provide a device of this character which embodies a suspension harness equipped with a seat which will permit the operator to stand erect therein or to sit upon the seat while working.

With the preceding and other objects and advantages in mind, the invention consists in the novel combination of elements, constructions and arrangement of parts and operations to be hereinafter enlarged upon, claimed and illustrated in the accompanying drawing wherein:

Figure 1 is a front elevation of the device showing a person supported therein;

Figure 2 is a view taken at right angles to Figure 1, the dotted lines indicating the position of the person's body while seated;

Figure 3 is a horizontal sectional view taken on line 3—3 of Figure 2; and

Figure 4 is a fragmentary perspective of one of the stirrups and its supporting straps therefor embodied in the invention.

Referring in detail to the drawing wherein like characters of reference designate like parts throughout the several views, the numeral 5 designates a pair of straps arranged in crossed relation intermediate their ends and secured together at a point designated at 6. The straps 5 are provided with buckles 7 to permit the straps to be lengthened or shortened. These straps 5 are connected adjacent the point 6 with a metal circular

band 8. Depending from the extremities of each strap 5 is a stirrup 9 in which the operator is permitted to stand when desired. 55

A waist encircling band 10 is attached to the straps 5 and is provided with a hinged joint 11 at the rear and a latch 12 at the front. Depending from the band 10 is a strap 13 carrying a seat 14. A back rest 15 60 is attached to the band 10 rearwardly thereof. Thigh encircling straps 16 are attached to the straps 5 below the band 10 while ankle straps 17 are attached to the straps 5 slightly above the stirrups 9. A loop or eye 19 is 65 carried by the straps 5 at the point of intersection of the same and is adapted to be engaged by a suspension hook 20 of a suitable hoist extending to the top of the structure to be reached (not shown). 70

From the disclosure it will be manifest that the operator will be safely strapped in the device and yet have free body movement.

It will also be seen that when the operator 75 does not desire to stand as illustrated in Figures 1 and 2, he may assume a seated position.

It is to be understood that the form of my invention herein shown and described is to be 80 taken as a preferred example of the same, and that various changes in the shape, size and arrangement of parts may be resorted to without departing from the spirit of the invention or the scope of the subjoined 85 claims.

Having thus described my invention, what I claim as new and desire to secure and protect by Letters Patent of the United States, is:

1. A suspension device for workmen comprising a pair of supporting straps, stirrups carried thereby, means for suspending the supporting straps, a hinged band carried by the straps and adapted to pass around the 95 waist of the workman, and a seat depending from the band.

2. A device of the character described including a pair of straps arranged in crossed relation intermediate their ends and connected together at such point, a stirrup carried by the extremities of each strap, a hinged band carried by the straps adapted to pass around the operator's body at the waist, a 100

latch carried by the free ends of the band, a seat suspended from the band, and means for suspending the supporting straps.

3. A workman's seat comprising a pair of supporting straps adapted to extend longitudinally at the front and rear of the workman and having their intermediate parts arranged in crossed relation and connected together, a band fixed to the straps adjacent

their point of intersection, a hinged band 10 attached to the straps to pass around the waist of the workman, thigh and ankle encircling straps carried by the supporting straps, a seat suspended from the hinged band, and means for suspending the supporting straps 15 at their point of intersection.

PASQUALE GIANNONE.
